UNITED STATES PATENT OFFICE.

HERMAN F. BALL, OF NEW YORK, N. Y., ASSIGNOR TO SAMUEL G. ALLEN, TRUSTEE,
OF NEW YORK, N. Y.

APPARATUS FOR BURNING PULVERIZED FUEL.

2,117,780.

Specification of Letters Patent.

Patented Nov. 17, 1914.

Application filed August 18, 1912. Serial No. 225,275.

To all whom it may concern:

Be it known that I, HERMAN F. BALL, of the borough of Manhattan, in the city, county, and State of New York, have invented a certain new and useful Improvement in Apparatus for Burning Pulverized Fuel, of which improvement the following is a specification.

The object of my invention is to enable effectively and economically practised in the boilers of locomotive engines under the varying operative conditions to which these boilers are subjected in practical railroad service, and my invention, generally stated, consists in the combination of power actuated mechanism for conveying pulverized fuel into a boiler furnace, and for supplying a blast of air to the fuel therein; means for exhausting the gases of combustion from the furnace, and manually operable means for independently controlling the operation of said conveying and supplying mechanisms and exhausting means.

25 The improvement claimed is hereinafter fully set forth.

In the accompanying drawings: Figure 1 is a diagrammatic vertical longitudinal central section through a locomotive and a portion of its tender, illustrating and embodiment of my invention; and, Fig. 2, a sectional view of a variable exhaust mechanism which may be substituted therein.

My invention is herein exemplified as applied in connection with a locomotive engine which, otherwise, is of one of the present standard types, known as the "Mikado" or "2-8-0."

The boiler comprises, as in ordinary practices, a firebox or furnace, 1, a waist or cylindrical body portion, 2, and a smoke box, 3. The firebox is closed at bottom by a tight ash pan, 4, and a plurality of fire tubes, 5, extends through the waist, from the firebox to the smoke box, which latter is provided with an open stack, 6. A conical casing, 7, in the smoke box, conveys the products of combustion from the tubes to the casing of an exhaust fan, 8, located at the front of the smoke box, and rotated by a suitable motor, 9, which, in the instance shown, is electrically actuated; and effects an exhausting draft by which the products of combustion are drawn into the stack and discharged therefrom to the atmosphere.

The exhaust steam is, in the instance shown in Fig. 1, discharged from the cylinders, 21, to the atmosphere through an open or unrestricted exhaust pipe, 22. The pulverized fuel used for the generation of steam in the boiler is carried in a fuel bin, 10, located, above the water bottom of a tank, 11, supported on the frame, 12, of the tender.

In the practice of my invention, pulverized fuel from the bin, 10, is delivered to a power actuated blower, 13, by which it is conveyed through a conduit, 14, into the firebox, below a brick arch, 15, with which the firebox is preferably fitted. The blast of air furnished by the blower, 13, is comparatively small in volume and high in determined pressure. As the fuel passes out of the conduit, 14, it meets, and is mingled with, a supply of air to properly support combustion, which is furnished, in larger volume and at lower pressure, by a power actuated blower, 16, the supply of air being delivered therefrom through a conduit, 17, discharging in the firebox adjacent to the outlet of the conduit, 14. Upon the completion of the combustion of the pulverized fuel in the firebox, the gaseous products of combustion are drawn therefrom, through the tubes, 5, by the exhaust fan, 8, and discharged through the stack. The blowers, 13 and 16, are rotated by independent motors, 13^a and 16^a, respectively, electric current for which, and for the fan motor, 9, is supplied by a generator, 18, actuated by a turbine motor, 18^a, to which steam is supplied through a valve governed pipe, 19, leading from a turret, 20, on the boiler.

In order to effectively maintain combustion under varying conditions of service, it is necessary that the pressure and volumes of the supplies of air from the blowers, 13 and 16, respectively, and the speed of rotation of the exhaust fan, 8, shall properly be proportioned and independently regulated and adjusted by the operator, as may, from time to time, be required. To this end, I provide a controller, 23, which is located in the cab, 24, of the locomotive, within convenient reach of the operator, and is connected by conductors, 25, with the generator, 18, and provided with switches, 26, 27, and 28, by which the current from the generator may be independently and regulably supplied to or cut off from the motors, 9, 13^a, and 16^a, respectively, as desired, said motors 110

being connected with the switches by conductors, 26^a, 27^a, and 28^a, respectively. While I have herein illustrated the blowers and exhaust fan as operated by electric motors, it will be obvious that, if preferred, fluid pressure motors of any known and desired type, actuated by steam from the boiler or by air under pressure, may be substituted therefor. It will also be apparent that instead of effecting the draft through the tubes by an exhaust fan, as herein set forth, any suitable variable exhaust mechanism may be used for the purpose, as for example, that shown in Fig. 2, in which a conical plug, 29, is raised and lowered within the exhaust pipe, 22, and thereby contracts or enlarges the discharge area through a contracted nozzle, 22^a, connected to the outlet end of the exhaust pipe, in order to increase or diminish the exhausting action of the steam blast therefrom, as the case may be.

I claim as my invention and desire to secure by Letters Patent:—

1. In an apparatus for burning pulverized fuel, the combination of mechanism for conveying pulverized fuel into a boiler furnace, mechanism for supplying a blast of air to the fuel when delivered thereinto, power operated means for independently actuating said mechanisms, means for exhausting the gases of combustion, and manually operable means for independently controlling the operation of said conveying and supplying mechanisms and exhausting means.
2. In an apparatus for burning pulverized fuel, the combination of mechanism for conveying pulverized fuel into a boiler furnace, mechanism for supplying a blast of air to the fuel when delivered thereinto, motors, each independently actuating one of said mechanisms, means for exhausting the gases of combustion, and manually operable means for independently controlling the operation of said motors and of the exhausting means.
3. In an apparatus for burning pulverized fuel, the combination of mechanism for conveying pulverized fuel into a boiler furnace, mechanism for supplying a blast of air to the fuel when delivered thereinto, means for exhausting the gases of combustion, motors,

independently actuating said mechanisms and the exhausting means, and manually operable means for independently controlling the operation of said motors.

4. The combination with a steam boiler, of mechanism for conveying pulverized fuel into the furnace thereof, mechanism for supplying a blast of air to the fuel when delivered thereinto, motors, each independently actuating one of said mechanisms, means for operating said motors by steam generated in the boiler, means for exhausting the gases of combustion from the furnace, and manually operable means for independently controlling the operation of said motors and of exhausting means.

5. The combination, with a steam boiler, of a receptacle for pulverized fuel, a conduit leading therefrom to the boiler furnace, a blower discharging into said conduit, a second conduit leading into the furnace and having its outlet adjacent to that of the first specified conduit, a blower discharging into said second conduit, an exhaust fan for exhausting the products of combustion from the furnace, motors, independently actuating said blowers and exhaust fan, and manually operable means for independently controlling the operation of said motors.

6. The combination, with a steam boiler, of a receptacle for powdered fuel, a conduit leading therefrom to the boiler furnace, a blower discharging into said conduit, a second conduit leading into the furnace and having its outlet adjacent to that of the first specified conduit, a blower discharging into said second conduit, an exhaust fan for exhausting the products of combustion from the furnace, electric motors, independently actuating said blowers and exhaust fan, an electric generator operated by steam from the boiler, a controller, conductors, connecting said controller with the generator and motors, and switches, independently governing the supply of electric current to the motors.

HERMAN F. BALL.
